(57) CLAIM

The ornamental design for a garment collar, as shown and described.

DESCRIPTION

FIG. 1 is a left perspective view of a garment collar showing my new design buttoned;
FIG. 2 is a rear right perspective view thereof;
FIG. 3 is a front view thereof;
FIG. 4 is a rear view thereof;
FIG. 5 is a right side view thereof;
FIG. 6 is a top view thereof;
FIG. 7 is a bottom view thereof;
FIG. 8 is a rear right perspective view thereof, showing the garment collar unbuttoned;
FIG. 9 is a right side view thereof;
FIG. 10 is a top view thereof; and
FIG. 11 is a front view thereof.

FIG. 12 is a buttoned front left perspective view of a second embodiment of a garment collar showing my new design;
FIG. 13 is a rear right perspective view thereof;
FIG. 14 is a front view thereof;
FIG. 15 is a rear view thereof;
FIG. 16 is a left side view thereof;
FIG. 17 is a right side view thereof;
FIG. 18 is a top view thereof;
FIG. 19 is a bottom view thereof;
FIG. 20 is an unbuttoned rear right perspective view thereof;
FIG. 21 is a front view thereof;
FIG. 22 is a left side view thereof;
FIG. 23 is a right side view thereof; and,
FIG. 24 is a top view thereof.

The garment shown in broken lines depicts environment included to show the garment collar in positions of use and forms no part of the claimed design.

1 Claim, 22 Drawing Sheets
